UNITED STATES PATENT OFFICE.

WILLIAM L. BRALEY AND HENRY N. FAAS, OF SPRINGFIELD, OHIO, ASSIGNEES TO THE AMERICAN SEEDING MACHINE COMPANY, OF SPRINGFIELD, OHIO, A CORPORATION OF OHIO.

CULTIVATOR.

Application filed May 21, 1923. Serial No. 640,343.

To all whom it may concern:

Be it known that we, WILLIAM L. BRALEY and HENRY N. FAAS, citizens of the United States, residing at Springfield, in the county of Clark and State of Ohio, have invented certain new and useful Improvements in Cultivators, of which the following is a specification.

This invention relates to improvements in 10 cultivators, it more particularly relating to single row cultivators in which two gangs of cultivator shovels are employed.

An object of the invention is to provide 15 improved means whereby each gang of shovels may be raised from the ground independently of the other gang, together with means for changing the center of gravity of the machine when such operation takes place by shifting rearwardly the carrying 20 wheel upon that side of the machine which supports the gang of shovels which has been raised.

A further object of the invention is to provide improved means for shifting the shovel 25 beams and carrying wheels laterally to cause the machine to follow the corn rows.

In the accompanying drawings:

Fig. 1 is a view in perspective looking from the rear of a cultivator embodying the 30 improvements.

Fig. 2 is a side elevation.

Fig. 3 is a detail of the axle construction.

Fig. 4 is a longitudinal section of the parts shown in Fig. 3.

Fig. 5 is a plan view of a portion of the machine.

Fig. 6 is a side elevation of a portion of the machine.

Referring to the drawings, 1 represents a 40 pair of frame members which have their forward ends converged and secured to the tongue 2 and their rear ends secured to a bracket 3 which in turn is clamped to a tubular axle member 4 by clamping mem-

bers 5 and bolts 6, which bolts also secure in 45 position the brackets 6' to which the seat supporting members 7 are fastened. A transversely extending rail 8 is fastened to the forward ends of the side frame members 1 through the medium of brackets 9 and a draft bar 10 is supported from the rail 8 through the medium of hangers 11, the upper portion of each of which is of yoke 50 form and has journalled therein an anti-friction roll 12 which rides on top of the rail 8,

Shovel beams are indicated at 13 and each shovel beam is connected to a head 14 which is pivotally mounted on the draft bar 10.

Each of the carrying wheels 15 is journaled upon the horizontal portion 15' of a 60 spindle which has a vertical portion 15" rigidly secured in a sleeve 16 by clamping bolts 17 and rivets 18. Each end of the tubular axle 4 has journalled therein a transversely-extending horizontal portion 19 of an 65 axle spindle which has a longitudinally-extending portion 20 and a vertical portion 21 which is journaled in the sleeve 16. The part 19 of the spindle is held against endwise movement in the axle by a cotter pin 70 19' which extends through an opening 19" in the part 19 which is elongated sufficiently to permit a limited rotary movement of the spindle part 19 in the axle. Each of the beams 13 has extending downwardly from 75 its forward end a rigid arm 22 the lower end of which is preferably braced from the beam by a brace rod 23. Each of the sleeves 16 is pivotally connected with the corresponding arm 22 by a rod 24 which is preferably 80 formed in two parts secured together by bolts 25 so that the length thereof may be adjusted.

A rock shaft 26 square in cross-section has mounted thereon bearing sleeves 27 85 which are journaled in brackets 28 secured to the side frame members 1. A main lever 29 is rigidly secured to one end of this rock shaft and has a pawl 30 which cooperates with the teeth of a curved rack 31. Rigidly secured to the rock shaft is a pair of brackets 32, one near each end thereof, and to each of these brackets 32 is pivotally connected, as at 33, an auxiliary lever 34 which has a pawl 35 cooperating with the teeth 36 90 on the upper end of the bracket. The lower end of each lever 34 has a forwardly-projecting arm 37 which is connected with the corresponding beam 13 by the rod 38.

In the operation of the devices as thus far 100 described, both beams may be simultaneously raised by pulling the lever 29 rearwardly which rocks the shaft 26 and causes the arms 37 to raise the beams through the links 38. As the beams are raised, the rigid arms 22 105 through the links 24 shift the wheels rearwardly, the transversely-extending horizontal portions 19 of the wheel axles turning in the tubular axle 4 to permit of this movement. If, however, it is desired to raise but 110

one only of the beams, the operating lever 34 corresponding to that beam is operated by pulling the same rearwardly, thereby shifting the carrying wheel 15 on that side 5 of the machine through the arm 22 and link 24 attached to the beam which is raised.

Another feature of the invention is the means which we employ for shifting the beams and carrying wheels laterally to cause 10 the same to follow the corn rows, this feature being best illustrated in Figs. 5 and 6. Pivottally connected to each of the extensions 7' of the seat supporting member 7 is a foot lever 40 which has pivottally connected therewith one end of a link 41 the opposite end of which is pivottally connected to a pair of toggle jointed levers 42 and 43 at the point of their juncture. The lever 43 is pivottally connected to the bracket 9 15 previously referred to while the lever 42 is pivottally connected to a bolt 44 which is carried by the bracket 45 secured to the draft bar 10. The upper end of each sleeve 16 has laterally projecting trunnions 46 to 20 which are secured the rear end of a bifurcated arm 47, the forward end of which is secured to a head 11' pivottally connected with the bracket 11.

By this arrangement the beams and 30 wheels may be shifted in either direction by depressing one or the other of the foot levers 40, so as to shift the draft bar endwise on the rail 8, the toggle-jointed arrangement described furnishing increased 35 power for this shifting operation over arrangements previously employed for the purpose and also providing for a greater range of shifting movement.

Also pivoted on the bolt 44 is a beam 40 spacing member 48 which has three arms two of which are connected to the beam heads 14 by the links 49 and the other of which is connected to a lever 50 by a link 51, this beam spacer, however, forming no part 45 of our present invention.

Having thus described our invention, we claim:

1. In a cultivator, a pair of pivoted shovel beams, supporting wheels, means for simultaneously raising said beams and shifting said wheels to balance the beams when raised, and additional means for raising each of said beams independently of each other and shifting the adjacent wheel 55 to balance the beam which has been raised.

2. In a cultivator, a frame, a pair of supporting wheels for said frame, a pair of shovel beams having their forward ends pivottally connected with said frame, devices 60 located on said frame for simultaneously raising said beams, an independent device located on said frame for independently raising said beams, and means whereby when both beams are raised both supporting wheels are shifted relatively to the frame and when a 65

single beam is raised the adjacent supporting wheel only is shifted relatively to the frame.

3. In a cultivator, a frame, a pair of supporting wheels for said frame, a pair of shovel beams having their forward ends 70 pivottally connected with said frame, a rock shaft supported on said frame, a pair of levers pivottally supported by said shaft and connected with the respective beams, whereby each of said beams may be independently 75 raised, together with means for locking said levers to said shaft, a main lever connected with said shaft whereby both of said beams may be simultaneously raised, together with means for locking said main lever, and means for shifting an adjacent supporting wheel relatively to the frame when either one of said beams is raised and for shifting both of said wheels relatively to the frame 80 when both of said beams are raised.

4. In a cultivator, a frame, a pair of supporting wheels for said frame, a spindle for each wheel, a second spindle member rotatably connected with said frame and having a swiveled connection with said first spindle, a pair of shovel beams having their forward ends pivottally connected with said frame, devices located in said frame for simultaneously raising said beams, additional devices located on said frame for independently raising said beams, a rigid arm connected with each beam near the forward end thereof, a link pivottally connecting said arm with one of said wheel spindles whereby 95 when both beams are raised both supporting 100 wheels are shifted relatively to the frame and when a single beam is raised the adjacent supporting wheel only is shifted relatively to the frame.

5. In a cultivator, a main frame, a pair of supporting wheels for said frame, each of said wheels being associated with a spindle which includes a horizontal portion rotatably connected with said frame, a rock shaft supported on said frame, a pair of levers pivottally supported by said rock shaft and connected with the respective beams, means for locking said levers to said shaft, a main lever connected with said shaft, means for locking said main lever, the arrangement being such that when said shaft is rocked by said main lever both beams are raised and when each individual one or the other of said levers is operated but a single beam is raised, a rigid arm connected with the forward end of each of said beams, and a link connecting each of said arms with an adjacent wheel spindle whereby raising of both beam shifts both of said supporting wheels and the raising of a single beam shifts only one of said supporting wheels.

In testimony whereof, we have hereunto set our hands this 18th day of May 1923.

WILLIAM L. BRALEY,
HENRY N. FAAS.
